(57) CLAIM

The ornamental design for a clasp for a handbag as shown and described.

DESCRIPTION

FIG. 1 is a front perspective view of a clasp for a handbag showing my new design in the environment of use of a handbag frame;

FIG. 2 is a left side view thereof;

FIG. 3 is a right side view thereof;

FIG. 4 is a front view thereof;

FIG. 5 is a back view thereof;

FIG. 6 is a top view thereof;

FIG. 7 is a bottom view thereof;

FIG. 8 is a front perspective view of the clasp for a handbag shown in the environment of use of a handbag;

FIG. 9 is a left side view thereof;

FIG. 10 is a right side view thereof;

FIG. 11 is a front view thereof;

FIG. 12 is a back view thereof;

FIG. 13 is a top view thereof; and,

FIG. 14 is a bottom view thereof.

The broken lines in the figures depict portions of the clasp for a handbag that form no part of the claimed design. The broken lines showing of a handbag frame and handbag in the figures depicts unclaimed environment.
